UNITED STATES PATENT OFFICE.

VICTOR H. ROEHRICH, OF ST. PAUL, MINNESOTA.

DESIGN FOR A LIGHTING-POST.

52,254.

Specification for Design.

Patented Aug. 6, 1918.

Application filed November 13, 1917. Serial No. 201,852. Term of patent 14 years.

To all whom it may concern:

Be it known that I, VICTOR H. ROEHRICH, a citizen of the United States, residing at St. Paul, county of Ramsey, and State of Minnesota, have invented a new, original, and ornamental Design for Lighting-Posts, of which the following is a specification, reference being had to the accompanying drawings, forming part thereof.

Figure 1 is a side elevation of a lighting post showing my new design.

Fig. 2 is a cross section on the line 2—2 of Fig. 1.

I claim:

The ornamental design for a lighting post as shown.

VICTOR H. ROEHRICH.
